UNITED STATES PATENT OFFICE.

THOMAS J. ALDRIDGE AND MATTHEW A. REILLY, OF ROCHESTER, NEW YORK; SAID
REILLY ASSIGNOR TO SAID ALDRIDGE.

SHOE CONSTRUCTION.

1,101,379.

Specification of Letters Patent. Patented June 23, 1914.

Application filed October 2, 1913. Serial No. 793,005.

To all whom it may concern:

Be it known that we, THOMAS J. ALDRIDGE and MATTHEW A. REILLY, citizens of the United States, residing at Rochester, in the 5 county of Monroe and State of New York, have invented certain new and useful Improvements in Shoe Constructions, of which the following is a specification.

The present invention relates to improvements in boot and shoe constructions and lies 10 particularly in the provision of a stiffening member coöoperating with a support, whereby not only is the boot or shoe prevented from losing its original shape, but a proper 15 support for the arch of the foot is thereby provided.

We are aware that constructions of this 20 nature have been proposed heretofore but certain disadvantages have arisen incidental to their use and it has been our object in the present invention to overcome these disadvantages by employing a metallic or similar stiffening member in conjunction with a particularly shaped counter.

25 With the above and other objects in view, this invention consists in the construction, combination, and arrangement of parts, all as hereinafter more fully described, claimed and illustrated in the accompanying drawings, wherein—

30 Figure 1 is a perspective view of an insole structure for a boot, shoe or the like, provided with our stiffener and support. Fig. 2 is a transverse sectional view taken about on the line 2—2 of Fig. 1; Fig. 3 is a perspective view of the arch support alone; Fig. 4 is a longitudinal sectional view taken about on the line 4—4 of Fig. 1; and Fig. 5 is a 35 diagrammatic view showing a modified construction of the invention, with the counter and arch support extended around the inner and outer sides of the insole.

40 Throughout the following detail description and on the several figures of the drawings, similar parts are referred to by like 45 reference characters.

45 It is to be noted that in structures such as are comprehended in this application a very slight change either in length or material 50 results in certain advantages, and we have therefore taken this into consideration in the construction of our invention. To this end, and referring to the drawings, 1 indicates an insole structure of the usual material and 55 shape, according to the general sizes, to

which is secured in any desired manner the counter 2. The counter 2 extends preferably around the outer portion of the insole 1 to a point ending with the heel of the foot of the wearer, while on the inner side, said 60 counter extends to a point opposite the first joint of the foot bones. The counter 2 is of the usual stiff leather and shaped to conform to the heel and instep of the foot along its elongated side, designated by the numeral 65 2'. Prior to the attachment of the counter 2 to the insole 1 it is split longitudinally along the inner side 2', preferably from its bottom, and between the two layers or walls thus formed an arch support 3 is inserted. 70 The arch support 3 is elongated and conforms to the shape of the counter 2 and necessarily to the shape of the foot, as above described with reference to the counter. It will be obvious that to depend upon the stiff leather counter 2 entirely to hold the shape and support the arch of the foot as desired would result disastrously when the leather had become softened by moisture from within, or perspiration, and from moisture 80 externally, which would cause the structure to fall down. The moisture from within also softens the counter and sometimes rubs the foot of the wearer. We have, therefore, employed the arch support 3 which is prefer- 85 ably of metal such as steel, or it may be of fiber or like hard substance, and by making the same of proper shape not only is the original shape of the shoe held but the arch along which it extends is supported, the 90 plate spanning the arch of the foot so that its bearing is upon the heel at its rear end and upon the toe portion of the structure at its front end.

95 It will be apparent that a shoe provided with the arch support herein described may be of the proper size to fit the foot of the wearer and the necessity of using a larger size in order to accommodate a removable arch prop sometimes inserted inside of the 100 shoe is not necessary.

105 As will be obvious, the invention herein described is particularly useful when employed in the construction of low shoes, slippers, pumps or the like, because such articles are predisposed to become misshapen from the lack of support in the ordinary construction. Not only does the extension of the counter to the ball or toe portion of the shoe resist primarily the lateral 110

stresses or pressure of the foot against the shoe, but the employment of the metallic arch support therewith takes up the vertical or downward pressure against said shoe.

5 The metallic plate 3 is easily inserted between the walls of the counter, the lower edges of which may then be readily bent laterally and fastened beneath the inner sole 1, and it will be understood that the counter

10 as well as the plate may be extended around both sides of the inner sole, conforming to the shape of the foot, as most clearly shown in the diagrammatic view of Fig. 5 wherein the numeral 1 designates the inner sole,

15 the numeral 2" the counter secured thereto in the unusual manner, and the numeral 3' the metallic arch support coöperating with said counter.

Having thus described the invention, what

20 is claimed as new is:

The combination with a boot or shoe comprising an insole and a counter secured thereto, said counter extending only from

the front portion of the heel at one side around the heel and along the opposite side 25 of the shoe to a point beyond the arch of the same and opposite the large toe joint, said counter being split upwardly from its bottom portion along the elongated side of the same, of a metallic arch supporting 30 member disposed in the split of the counter on said elongated side, conforming substantially to the shape of the elongated portion of the counter, and having a length and a bearing on the sole from approximately the 35 base of the arch at the large toe portion to the base of the arch at the heel on the same side of the shoe.

In testimony whereof we affix our signatures in presence of two witnesses.

THOMAS J. ALDRIDGE.
MATTHEW A. REILLY.
